UNITED STATES PATENT OFFICE.

BOYD B. KEITH, OF MANSFIELD, OHIO.

TOY AIRSHIP.

1,427,396.

Specification of Letters Patent. Patented Aug. 29, 1922.

Application filed September 23, 1920, Serial No. 412,168. Renewed November 25, 1921. Serial No. 517,812.

To all whom it may concern:

Be it known that I, BOYD B. KEITH, a citizen of the United States, and a resident of Mansfield, in the county of Richland and State of Ohio, have invented a new and Improved Toy Airship, of which the following is a full, clear, and exact description.

This invention relates to improvements in toy airships, an object of the invention being to provide a toy which can be manufactured and sold at an extremely low price and which will simulate an airship of the dirigible type.

A further object is to provide a toy of the character stated which can be readily manufactured and sold in knock-down form so that the several parts can be conveniently packed in an envelope and which can be easily assembled by any one of average intelligence to form an extremely ornamental, attractive and interesting toy.

With these and other objects in view the invention consists in certain novel features of construction, and combinations and arrangements of parts as will be more fully hereinafter described and pointed out in the claims.

In the accompanying drawings—

Figure 1 is a perspective view illustrating my improved toy.

Figure 2 is a view in transverse section on the line 2—2 of Figure 1.

Figure 3 is a view in longitudinal section through the toy.

Figures 4, 5, 6, 7, 8, 9, 10, 11 and 12 are detail views illustrating the different parts of the toy before assemblage.

1 represents a balloon which is of the elongated type shown and which, when blown up to the desired size and the air enclosed, is provided at its respective ends with cones 2, 2. These cones are preferably of paper and are formed from blanks, such as shown in Figure 7, and secured by adhesive or other suitable material to hold the cones in proper formation and connected to the ends of the balloon.

3 represents a car which is suspended from the balloon 1. This car 3 is preferably formed from a blank, such as shown in Figure 8, with the ends 4 of the blank secured to the sides thereof by means of stickers 5. These stickers comprise preferably small circular paper disks having adhesive thereon which form an effective coupling means to hold the box in proper shape.

The box or car 3 is formed with a web 6 at its upper edge, this web being of double thickness as indicated by the blank, and laterally projecting tongues 7 are formed 60 at the ends of the web and have a bearing against the two surfaces of the balloon 1.

The web 6 is perforated throughout its length as shown at 8, and a cord 9 is passed around the balloon 1 and through the perforations 8 and secured in any approved manner to effectually secure the car 3 to the balloon 1 as clearly indicated in the drawings. A second cord 10 is secured to the cord 9 and acts as a suspension device 70 which may be attached to a stick or to a string so that the toy may be readily moved about.

A short imitation shaft 11 is secured in the rear end of the car 3 and supports an imitation propeller 12, the latter being preferably of paper or any other suitable material. A string 13 connects the forward end of the car with the forward cone 2 and supports a flag 14, the latter being secure to the 80 cord by stickers 5 as above described.

In Figures 4 to 12 inclusive, I illustrate the several parts which go to make up the toy, and these parts are sold as independent parts and assembled in an ordinary envelope so 85 that the purchaser can easily and quickly construct the toy, thus adding to the attractiveness of the same.

This toy can be manufactured and sold at an extremely low price, can be assembled by 90 any one of average intelligence, and when in completed form, will be ornamental and attractive in appearance and simulate the appearance and actions of a dirigible type 95

Various slight changes might be made in the general form and arrangement of the parts described without departing from the invention, and hence I do not limit myself to the precise details set forth, but consider myself at liberty to make such changes and alterations as fairly fall within the spirit and scope of the appended claims.

I claim:

1. A toy airship, comprising an elongated balloon, cones on the ends of the balloon, an imitation car suspended from the balloon, a cord connecting the balloon and car, and a suspension device connected to the cord. 105

2. A toy airship, comprising an elongated balloon, cones on the ends of the balloon, an 110

- imitation car suspended from the balloon, an imitation propeller on the end of the car, a cord connecting the balloon and car, and a suspension device connected to the cord.
- 5 3. A toy airship, comprising an elongated balloon, a car below the balloon, a perforated web on the upper portion of the car, and a string passed around the balloon and through the perforations of the web.
- 10 4. A toy airship, comprising an elongated balloon, a car below the balloon, a perforated web on the upper portion of the car, a string passed around the balloon and through the perforations of the web, and 15 a second string connected to the first-mentioned string and acting as a support therefor.
- 5 5. A toy airship, comprising an elongated balloon, a car below the balloon, a perforated web on the upper portion of the car, a string passed around the balloon and through the perforations of the web, and laterally projecting tongues on the web engaging the under face of the balloon.
- 25 6. A toy airship, comprising an elongated balloon, a car below the balloon, a perforated web on the upper portion of the car, a string passed around the balloon and through the perforations of the web, and a string passed around the balloon and through the perforations of the web, an imitation shaft projecting from the rear 30 end of the car, an imitation propeller on the shaft, a string connecting the forward end of the balloon and the forward end of the car, and a flag connected to said last-mentioned string.
7. A toy airship, comprising a balloon, a blank adapted to be folded to form a car, a string adapted to secure the car to the balloon, and blanks adapted to be shaped to form cones for the ends of the balloon.
8. A toy airship, comprising a balloon, a blank adapted to be folded to form a car, a string adapted to secure the car to the balloon, blanks adapted to be shaped to form cones for the ends of the balloon, a toy propeller adapted to be connected to the rear 40 end of the car, a flag, and a string adapted to connect said flag to the forward end of the car.

BOYD B. KEITH.
